UNITED STATES PATENT OFFICE.

WILLIAM WADE, OF TRENTON, MICHIGAN, ASSIGNOR OF ONE-HALF TO
GEORGE B. DAVIS, OF UTICA, MICHIGAN.

RAILWAY-TIE.

SPECIFICATION forming part of Letters Patent No. 683,531, dated October 1, 1901.

Application filed July 25, 1901. Serial No. 69,609. (No model.)

To all whom it may concern:

Be it known that I, WILLIAM WADE, a citizen of the United States of America, residing at Trenton, in the county of Wayne and State 5 of Michigan, have invented certain new and useful Improvements in Railway-Ties, of which the following is a specification, reference being had therein to the accompanying drawings.

10 My invention relates to a composite railway-tie in which the advantage of an elastic wood seat is combined with that of a metallic tie of maximum strength and minimum amount of metal and of such simple construction that it may be easily rolled and serve as a retainer for the wood cushion, in connection with a simple and strong track-fastening which connects the rails directly with the tie and permits the changing or renewal 15 20 25 of the wood cushion independently of the tie or track-fastening, all as more fully herein-after described, and shown in the accompanying drawings, in which—

Figure 1 is a perspective view of my improved tie with one of the track-rails secured in place upon the tie. Fig. 2 is an end elevation of the tie. Fig. 3 is a cross-section of the metal portion of the tie on line 3-3 in Fig. 1. Fig. 4 is a vertical longitudinal section 30 35 through the outer end of the tie substantially on line 4-4, Fig. 1. Fig. 5 is a detached perspective view of a portion of metal tie and of the two rail-hooks co-operating therewith, the tie being of slightly-modified construction.

A designates a metal tie, formed with a bottom *a* and two sides *b*, making it U-shaped throughout its entire length, which is that of the common wooden tie and adapted to be 40 formed by rolling, like other structural iron.

B designates the rails of the track.

C designates clamping-dogs for securing the rail to the tie, and D designates wooden blocks secured in the end of the tie and forming the 45 support and cushion for the rails. The clamping-dogs are flat metal strips or bars, each formed integrally on edge with an upwardly-projecting hook *f*, adapted to embrace the foot of the rail, and anchoring-pins *e*, formed at the 50 ends of the bar, adapted to engage and register with corresponding holes *g*, formed in

the sides of the tie for the purpose of anchoring the dogs to the tie. The wooden blocks are of a width to hold the dogs in position against the sides of the tie when driven into the end of the tie and of a height to hold the rail out of contact with the metallic portions of the tie, thereby forming a cushion for the rail and at the same time a locking key or wedge which secures the clamping-dogs in pairs in 55 60 65 the ends of the ties. To facilitate the driving in of these blocks, they may be made slightly wedge-shaped or merely beveled off at the inner ends, either on top alone or on the sides as well. To prevent the dogs from becoming loose in case of shrinkage of the wooden blocks, the dogs are curved, as shown, so that they form a strong spring, which will be flattened out against the sides of the tie when the blocks *D* are driven in. I also preferably 70 make the anchoring-hooks *e* sufficiently long to project well through the openings *g*, so that they could not possibly draw out of engagement therewith, and might even permit of their being bent over to clench on the outside. To provide for contingencies which might make it desirable, I also provide one or more holes *h* in each end of the tie for driving a nail through into the wooden block to hold it in place. Another provision of which 75 I might desire to avail myself in case the wooden blocks are of reasonably soft wood is to make the bottom of the tie corrugated, as shown in Fig. 5, so that the wood will press into the corrugations, and thereby become 80 85 90 more firmly seated, and the inner faces of the dogs in contact with the sides of the wooden blocks may be corrugated or roughened to any desired extent to prevent the displacement of the blocks.

My construction embodies no bolts and nuts and provides a fastening which is simple and strong and which provides a desirable amount of elasticity and thorough cushioning of the rails. There are but three different elements involved in the construction—namely, the ties, the dogs, and the wooden blocks—all of which are of simple manufacture.

What I claim as my invention is—

1. In a rail-fastening, the combination with a metallic U-shaped tie, of flat metal bars

5 detachably secured against vertical and longitudinal displacement on the inner faces of the sides of the tie, two on each end upon the opposite sides of the tie, and wooden blocks in the ends of the tie operating as a key or wedge to lock said bars in position in the tie against lateral displacement, said bars formed with a hook to engage the foot of the rails.

10 2. In a rail-fastening, the combination with a metallic **U**-shaped tie, of flat metal bars detachably secured against vertical and longitudinal displacement upon the inner faces of the sides of the tie, two in each end upon opposite sides of the tie, and wooden blocks 15 driven into the ends of the tie operating as a combined wedge or key to lock said bars in position in the tie against lateral displacement and as a bearing to support and cushion the rails, said bars having hooks projecting 20 above the wooden blocks and adapted to engage the foot of the rails and clamp it to the tie.

25 3. In a rail-fastening, the combination with a metallic **U**-shaped tie, of flat metal bars curved in their horizontal planes to form springs and detachably secured against vertical and longitudinal displacement on the inner faces of the sides of the tie, two in each end upon the opposite sides of the tie, and 30 wooden blocks in the ends of the ties between each pair of bars operating as a key or wedge to hold said bars in position in the tie against lateral displacement, said bars formed with hooks to engage the foot of the rails.

35 4. In a rail-fastening, the combination with a metallic **U**-shaped tie, of flat metal bars supported in the ends of the tie in contact

with the sides thereof and of corresponding height therewith, anchoring hooks or projections formed at the ends of said bars, holes in the sides of the tie into which said anchoring-hoops engage, a hook integrally formed on the upper edge of each bar and adapted to engage the foot of the rail, the hook of one bar on the outside and the hook of the other in the corresponding end of the tie on the outside, and wooden blocks driven into the ends of the tie and operating as a key or wedge between the under sides of the rail and the bottom of the tie and between the metal bars in the ends of the tie.

40 5. In a rail-fastening, the combination with a metallic **U**-shaped tie, of flat metal bars supported in the ends of the tie against the inner faces of the sides of the tie, two in each end, each bar provided with a hook for clamping the foot of the rail, one upon the outside and one upon the inside, interlocking means on said bars and the sides of the tie to prevent longitudinal and vertical displacement 45 of said bars, wooden blocks driven into the ends of the ties and operating as a key or wedge between the under side of the rail and the bottom of the tie and between the metal bars in the ends of the tie, and means on the 50 ends of the tie to prevent accidental displacement of the wooden blocks in said ties.

In testimony whereof I affix my signature in presence of two witnesses.

WILLIAM WADE.
